UNITED STATES PATENT OFFICE.

MATTHIAS BROCK, OF BOSTON, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

MACHINE AND METHOD FOR USE IN SHAPING UPPERS.

1,425,942.

Specification of Letters Patent. Patented Aug. 15, 1922.

Application filed October 22, 1917, Serial No. 197,863. Renewed July 25, 1921. Serial No. 487,519.

To all whom it may concern:

Be it known that I, MATTHIAS BROCK, a citizen of the United States, residing at Boston, in the county of Suffolk and State 5 of Massachusetts, have invented certain Improvements in Machines and Methods for Use in Shaping Uppers, of which the following description, in connection with the accompanying drawings, is a specification, 10 like reference characters on the drawings indicating like parts in the several figures.

This invention relates to the manufacture of shoes and is herein illustrated in its application to the making of stichdown shoes. 15 It will be recognized, however, that in many of its aspects the invention is not limited to the manufacture of shoes of that particular type, but is generally applicable to the making of shoes of various kinds.

20 It has heretofore been difficult and, in fact impossible from the practical standpoint to produce a shoe of the stichdown type in which the upper has the stretch removed and which is really lasted in the 25 sense that the upper of a welt shoe is lasted; that is, one that has been so stretched and shaped that it will retain its shape during long use as well as fit the wearer's foot. The preliminary molding of the forepart of 30 the upper by prior machines, such, for example, as that disclosed in United States Letters Patent No. 1,170,405, granted February 1, 1916, on application of M. Brock and L. M. Brown, has contributed very ma-

35 terially toward the production of a satisfactory stich-down shoe, but nevertheless the upper has not had the stretch removed from it as thoroughly as is desirable and as is possible by the pulling-over and lasting operations in the manufacture of welt shoes, for the reason, among others that in the prior machines the uppers are all treated alike and the different stretching characteristics of the individual upper are not taken care 40 of. Moreover, in the lasting of the better qualities of welt shoes upon a bed machine, the upper is wiped upwardly toward the sole of the shoe by the lasting wipers and thereby additionally stretched and conformed to the shape of the last. No operations corresponding very closely to the pull-

ing-over and bed lasting operations performed on welt work have hitherto been performed in the manufacture of stichdown shoes.

55 A general object of this invention is to provide a forming machine which will subject an upper to a treatment which will remove the stretch from the upper and conform the upper to the shape required in the 60 finished shoe, the machine illustrated being adapted also to form on the upper an outwardly directed sole attaching flange, the location of the angle of which with relation to the end and side portions of the upper is 65 not determined arbitrarily as in prior machines by the size to which the upper has been cut, but which is determined by the shape the upper is required to assume in the finished shoe, including receding or undercut 70 portions, and is formed in the upper at the line of junction of the end and sides of the upper with the sole, the angle being formed in the upper after the stretch has been removed irrespectively of the size to which the 75 upper has been originally cut.

A further object of the invention is to subject the upper during the forming operations to the action of heat of such quality as to render the upper soft and pliable during 80 the stretching operations and to dry and set the upper in the shape into which it is formed after the stretch is removed.

85 A feature of the invention consists in means for giving an upper a preliminary treatment which will remove the stretch from the upper, and means for wiping the upper about the toe in a direction toward the plane of the sole, with or without means for forming the margin of the upper projecting beyond the plane of the sole into an 90 outwardly directed flange. In the machine shown also, means is provided for assuming control of the upper after the stretching operation to hold the upper in stretched 95 condition while it is being further wiped in the manner described.

A further feature of the invention consists in means for subjecting the upper during the described operations to heat treatment such that during the stretching operation the upper will be rendered hot and

moist, and during the final wiping operation and the flanging operation the upper will be dried and permanently set in the final shape. Preferably also, means is provided for subjecting the upper between the stretching operation and the final wiping operation to an ironing operation with or without the action of a drying heat to assist in removing wrinkles and drying out the upper prior to the final wiping and flange setting operations.

Another feature of the invention consists in a novel organization comprising a form shaped to correspond to the forepart of the last, and toe embracing gripping jaws adapted to receive the upper in a substantially flat condition and having their gripping faces substantially parallel to the plane of the upper, together with means for effecting relative movement of the form and the jaws in a direction perpendicular to the plane of the upper to cause the upper to be stretched and wrapped in stretched condition around the form, the upper in the machine shown slipping from between the jaws and being then disposed at its margin perpendicular to the bottom of the form which represents the plane of the sole in the completed shoe.

A further feature of the invention consists in means for holding the upper margin in a position perpendicular to the bottom of the form, and means for wiping the upper at the end and sides of the form in a direction toward the bottom of the form and to shape the upper under the overhanging portions of the form. In the machine shown there are also provided means co-operating with the wipers for forming the portion of the upper extending beyond the bottom of the form into a sole attaching flange.

In a further aspect the invention provides a novel method for use in shaping upper materials. In accordance with the practice herein illustrated, the toe portion of the upper is molded off the last to give it substantially the shape which it is to have in the finished shoe by drawing it over a form and wiping it heightwise of the form, after which it is held from relaxing while its margin is shaped in accordance with the requirements of the particular type of shoe which is being made. The upper may, as illustrated, be wiped repeatedly heightwise of the form; and its margin also may be subjected to successive treatments, for example in stitchdown work by ironing it in substantially perpendicular relation to the plane of the bottom of the form and then wiping it outwardly to produce the flange characteristic of that type of shoe.

These and other features of the invention, and the novel method referred to, will appear more fully from the following detailed description when read in connection with

the accompanying drawings and will be pointed out in the appended claims.

In the drawings,

Fig. 1 is a side view of a machine embodying this invention;

Fig. 2 is a plan view of the machine, which is herein shown as a double machine, one half being designed for operating upon a left shoe upper and the other half upon a right shoe upper;

Fig. 3 is a sectional view on an enlarged scale of the upper shaping and heat treating mechanism;

Figs. 4, 5, 6 and 7 are detail sectional views showing successive stages in the operation of the machine upon a shoe upper;

Fig. 8 is a perspective view of a shoe upper after its treatment by the machine.

Referring to Fig. 1 of the drawings, the numeral 2 indicates the frame of the machine in which are journaled a drive shaft 4, and a cam shaft 6. Upon the shaft 6 are the cams from which the movements of the various operating parts of the machine are derived, and also a suitable clutch 8 operated by a treadle 10 by which the shaft 6 is permitted to receive from the drive shaft 4 a semi-rotation at each operation of the treadle.

The machine is preferably double, that is, comprises two machines operated by separate treadles, the machine on one side being designed to operate upon an upper for a right shoe, and the machine on the other side being designed to operate upon an upper for a left shoe. It will be understood that upon depression of its treadle either machine may be started and will stop with the upper in final shaped condition, as illustrated in Fig. 7, and may be left any required time, for example, while the operator is placing an upper for the corresponding shoe in the other machine and starting it by operating the second treadle. The first treadle may then be depressed to start the first machine which will stop with the parts in open position and the upper released.

Since the halves of the machine are substantially identical, it will be necessary only to describe one side of the machine, it being understood that the other side is identical except that it is designed for shaping the upper of a shoe for the other foot.

A last-like form 20 is provided to the shape of which the upper is to be formed or molded. The form 20 is supported upon a post 22 guided for vertical movement in the machine frame and arranged to be raised to move the form vertically by a lever 24 pivoted at 25 between its ends and having at one end a pin and slot connection 27 with the post 22 and at the other end carrying a cam roll 28 which travels in a path 29

formed in a cam block 30. A cross-head 40 is mounted on rods 42 which are arranged for vertical sliding movement in the machine frame. Upon the rods 42 beneath the cross-head 40 are shoulders 44 to effect positive raising of the cross-head, and on the rods 42 above the cross-head 40 are springs 46 engaging at their upper ends adjustable abutments 48 upon the rods 42, through which springs the cross-head is yieldingly depressed. The lower ends of the rods 42 have pin and slot connections at 50 with a lever pivoted at 52 between its ends and having on its rear end a roll 54 which engages a cam path 56 in the cam block 30. On the machine frame, Fig. 3, is a jaw plate 60 which embraces the toe portion of the form and is preferably formed adjacent to its inner edge with a rib or ribs 62. On the lower face of a part 63 attached to the cross-head 40 is a corresponding jaw plate 64 which, when the cross-head is depressed by the mechanism described, grips the projecting marginal portion of the flat upper against the jaw plate 60 or against the ribs 62 when these are provided. This operation is clearly illustrated in Fig. 4.

The form 20 is next raised vertically and causes all parts of the upper about the toe portion of the form to be stretched and wrapped over the toe portion of the form, as illustrated in Fig. 5, the margin of the upper slipping from between the jaw plates 60, 64 and being then disposed in a position perpendicular to the bottom of the form, that is, to the plane of the last bottom. During this treatment of the upper, the upper is subjected to moist heat, for example, by steam emitted from orifices 66 leading from a chamber 68 formed in the part 63, the chamber receiving steam from any suitable source through a flexible tube 70.

As successive portions of the upper are being stretched and drawn from the jaw plates 60, 64, it is desirable that any wrinkles which may have formed be smoothed out and the upper be partially dried before it is further treated. For this purpose the part 63 just above the jaw plate 64 is formed as a toe embracing ironing surface 76 which embraces the form in close conformity to its end and side faces, as shown in Figure 2, and engages the upper as it is being drawn from between the stretching jaws and effects upon it a rubbing or wiping action, while subjecting it to dry heat, due to heating of the parts by the steam in the chamber 68. Preferably means is provided to press the margin of the upper against the ironing surface 76 during its passage across that surface, not only to augment the ironing action of the surface 76 but also to effect a

gripping of the stretched upper after it passes from between the jaw plates and before control of it is assumed by the wiper plates, to be described. For this purpose there are arranged just beneath the form 20 two plates 78, 80 which are pivoted together at their inner ends by a halved joint, the pivot pin 83 of the joint extending downwardly and connecting the plates to a plate 82 arranged beneath it. The inner portions of these plates are cut away to permit the passage of the reduced upper end of the post 22 which supports the form 20. Between the plate 82 and a shoulder on the rod 22 is a washer 84 to provide a suitable bearing for the plate 82. The plate 82 projects beyond the form 20 and is bifurcated to receive the upper end of a lever 86 having therein a long slot 88 engaged by a pin 89 passing through the bifurcations of the plate 82. The lever 86 is pivoted at 90 to lugs on the machine frame and its lower end is pivoted to a link 92 extending to the rear of the machine where it is pivoted to the upper arm 94 of an angle lever fulcrumed at 95 on the frame and having on its other arm 96 a roll 97 which engages an edge cam 98 on the cam block 30. In the link 92 at 106 is a yielding connection which causes the first part 95 of the movement imparted by it to the plate 82 to be yielding. It will be seen that the cam through the connections described will cause the lever 86 to move the plate 82 toward the ironing surface 76 yieldingly. The plate 82 will, of course, move the plates 78, 80 to cause them to engage the upper on its inner face and force it yieldingly into contact with the ironing surface 76, as illustrated in Fig. 5. The plates 78, 80 are arranged to be separated about their pivot 83 in conjunction with their inward movement by means of pins 100, 101 seated in the form 20 and extending downwardly into inclined slots 102, 103 in the plates 78, 80. This construction causes the outer ends of the plates 78, 80 to be separated and forced against the ironing surface 76 at the sides of the toe as well as at the end of the toe. After the yield at 106 is taken up, the link 92 will act positively to advance the plates 78, 80 farther, for a purpose to be described. From the position shown in Fig. 5, the form 20 continues to rise and the upper is engaged by toe embracing wipers 110, 112 mounted between the part 63 and a member 113. The wipers are pivoted together at 114 and are provided with cam slots 116 which engage rolls 118 to control the closing movement of the wipers. The jaw member 64, the part 63, and the member 113 are rigidly connected together by bolts 119, and the part 63 is maintained in spaced relation from the member 113 to receive the wiper plates 110, 112 by end 130.

larged portions on the bolts 119 which also form pivots for the rolls 118 by which the closing movement of the wipers is controlled. Since the wipers in the construction shown are not required to perform any overwiping of the upper upon the last bottom, their movement may be slight, being as shown only sufficient to take care of the recession of the sides and toe end of the 10 form toward its bottom face. The wipers 110, 112 extend rearwardly of the machine and are slotted at 117 to receive pins 121 extending upwardly from a T-shaped slide 120 mounted for movement longitudinally 15 of the form 20 in the machine frame.

The slide 120 is bored to receive a plunger 122 having a pin and slot connection at 124 with the upper end of the arm 94 by which the plunger 122 is actuated. Between the 20 end of the plunger 122 and the end of the bore in the slide 120 is a spring 126 by which the slide 120 is actuated yieldingly from the plunger. Positive retraction of the slide 120 is effected from the plunger 25 by means of a pin 128 which engages a block 130 connected to the slide 120 by means of an adjusting screw 132. By adjusting the screw 132 the retracted position of the slide 120 and hence the open position of the wipers 110, 112 may be varied.

As the upward movement of the form 20 continues the wipers 110, 112 are advanced yieldingly through the mechanism described to engage the upper on the end and sides 35 of the form and wipe the upper downwardly toward the plane of the bottom of the form, as clearly illustrated in Figs. 5 and 6. When the plane of the bottom of the form has reached substantially the plane 40 of the lower face of the wipers, Fig. 6, the plates 78, 80 are advanced through the mechanism already described to turn outwardly the margin of the upper extending across their edge faces to form an outwardly extending flange, as shown in Fig. 45 7, the wipers at the same time acting to form the upper into the angle between the end and side faces of the form and the top faces of the plates 78, 80. The machine 50 stops with the parts in this position to allow the stock to set in the shape into which it has now been formed. It will be observed that the wipers receive the heat conducted from the steam heated part 63 55 which assists materially in causing the upper to set quickly in its molded form. The wiper plates 78, 80, being farther from the source of heat and having greater radiating surface, are less intensely heated than the 60 ironing surface 76 across which the upper has passed to effect partial drying out of the upper before the flange turning and flange setting operations.

While this side of the machine remains 65 in stopped position an upper may be intro-

duced into the corresponding mechanism of the other side of the machine and subjected to similar operations. By the time this has been effected, the mechanism of the first side of the machine may be restarted and the 70 molded upper removed from the machine. After this treatment the upper will retain its form and is ready for attachment of a sole or soles in the usual manner for completing the stitch-down shoe.

Since the movement of the form 20 is in a fixed vertical path, it is desirable to provide adjustment for the jaw plate 64 and the ironing surface 76 longitudinally of the form. To effect this, the member 113 80 to which the jaw 64, part 63 and the surface 76 are connected as described, is arranged for adjustment relatively to the cross-head 40. The member 113 has a rearward extension 140 having an upwardly extending lug in which is rotatably mounted a screw 142 having threaded engagement with the cross-head 40, as clearly shown in Fig. 3. By turning the screw the member 113 and its connected parts may be adjusted 85 longitudinally of the form 20. Should this adjustment be sufficient to interfere with the operation of the wipers 110, 112, the screw 132 may also be correspondingly adjusted to maintain the slots 116 and the 90 wipers in proper relation to the rolls 118.

Having fully described my invention, What I claim as new and desire to secure by Letters Patent of the United States is:—

1. In an upper forming machine, a form 100 having the shape which the forepart of the upper is to assume in the finished shoe, upper gripping means arranged to receive the marginal portions of the upper, means for moving the form and the gripping means 105 relatively to cause the upper to be wrapped about the form and progressively withdrawn from the gripping means, means for wiping the upper at the end and sides of the form toward the bottom of the form, 110 and means for bending outwardly the portion of the upper extending beyond the bottom of the form and pressing it against the wiping means.

2. In an upper forming machine, a form 115 having substantially the shape which the forepart of the upper is to assume in the finished shoe, upper holding means adapted to receive the marginal portion of an upper and hold it yieldingly, means for moving the form and holding means relatively to cause the upper to be wrapped about the form and progressively withdrawn from the holding means, and means for assuming control of the tensioned upper as it leaves the holding means to prevent retraction of the upper.

3. In an upper forming machine, a form 120 having the shape which the forepart of the upper is to assume in the finished shoe, up-

per holding means embracing the form adapted to receive the marginal portion of a flat upper and hold it yieldingly, means for moving the form and holding means relatively to cause the upper to be wrapped about the form and progressively withdrawn from the holding means, means for assuming control of the tensioned upper after it leaves the holding means to prevent retraction of the upper, and means for wiping the upper at the end and sides of the form toward the bottom of the form and causing it to conform intimately to the shape of the form.

4. In an upper forming machine, a form having substantially the shape which the forepart of the upper is to assume in the finished shoe, clamping means arranged to embrace the form and adapted to receive the marginal portion of an upper and hold it yieldingly, means for moving the form and clamping means relatively to cause the upper to be wrapped about the form and progressively withdrawn from the clamping means, and means for wiping the upper at the end and sides of the form toward the bottom of the form.

5. In an upper forming machine, a form having the shape which the forepart of the upper is to assume in the finished shoe, upper holding means embracing the form adapted to receive the marginal portion of an upper and hold it yieldingly, means for moving the form and holding means relatively to cause the upper to be wrapped about the form and progressively withdrawn from the holding means, and means for bending outwardly the portion of the upper that is below the bottom of the form.

6. In an upper forming machine, a form having substantially the shape which the forepart of the upper is to assume in the finished shoe, clamping means embracing the form adapted to receive the marginal portion of an upper and hold it yieldingly, means for moving the form and clamping means relatively to cause the upper to be wrapped about the form and progressively withdrawn from the clamping means, and means for wiping the upper progressively heightwise of the form as it is withdrawn from the clamping means.

7. In an upper forming machine, a form having substantially the shape which the forepart of the upper is to assume in the finished shoe, clamping means adapted to receive the marginal portion of an upper and hold it yieldingly, means for moving the form and clamping means relatively to cause the upper to be wrapped about the form and progressively withdrawn from the clamping means, and means independent of the form for engaging both the inner and outer faces of the upper and assuming control of the tensioned upper after it leaves

the clamping means to prevent retraction of the upper.

8. In an upper forming machine, a form having substantially the shape which the forepart of the upper is to assume in the finished shoe, yieldingly actuated upper holding means, adapted to receive the marginal portion of an upper and hold it yieldingly, means for moving the form and holding means relatively to cause the upper to be wrapped about the form and progressively withdrawn from the holding means, means for wiping the upper at the end and sides of the form toward the bottom of the form, and means for forming the margin of the upper extending beyond the wiping means into a sole attaching flange.

9. In an upper forming machine, a form having the shape which the forepart of the upper is to assume in the finished shoe, gripping means embracing the form adapted to receive the marginal portion of a flat upper and hold it yieldingly, means for moving the form and gripping means relatively to cause the upper to be wrapped about the form and progressively withdrawn from the gripping means, means for conforming the upper intimately to the shape of the form and determining the line where the upper meets the top of the sole, and means for bending outwardly the portion of the upper extending beyond the line so determined.

10. In an upper forming machine, a form having the shape which the forepart of the upper is to assume in the finished shoe, wiping means embracing the form and adapted for tucking the upper in around the edge of the form and shaping the margin of the upper into an outturned flange, and additional means arranged to act on the upper prior to said tucking and flange forming operations to stretch the upper.

11. In an upper forming machine, a form having the shape which the forepart of the upper is to assume in the finished shoe, clamping means embracing the form adapted to receive the marginal portions of a flat upper, said clamping means comprising a flat upper plate and a ribbed lower plate, the rib being parallel with the edge contour of the plate, and means for moving the form and clamping means relatively to cause the upper to be wrapped about the form and progressively withdrawn from the clamping means.

12. In an upper forming machine, a form having substantially the shape which the forepart of the upper is to assume in the finished shoe, holding means comprising plates yieldingly actuated relatively to hold the margin of the upper yieldingly, means for moving the form and holding means relatively to cause the upper to be wrapped about the form and progressively withdrawn from the holding means, and addi-

tional means for molding the portion of the upper extending beyond the bottom of the form into a sole attaching flange.

13. In a machine of the class described, 5 the combination of means for gripping the margin of a flat upper, a shoe forepart form having undercut or receding portions movable relatively to the gripping means to draw the upper from the gripping means and stretch it in a direction perpendicular to 10 the bottom of the shoe form, means for holding the stretched upper under tension after it leaves the gripping means, wiping means for wiping the stretched upper on the form 15 in a direction toward the bottom of the form and arranged for closing movement to shape the upper to the undercut portions of the form, and means for forming the portion of 20 the upper extending beyond the bottom of the form outward to form an outwardly directed flange upon the upper.

14. In a machine of the class described, 25 the combination of an upper gripper, a toe embracing wiping means arranged for closing movement, a form having the shape of the forepart of a shoe including receding or undercut portions adjacent to the bottom of the form, means for relatively moving the form and the other mentioned elements to 30 bring an upper overlying the form into position for operations of the wiping means, and means for operating the wiping means to do its work.

15. In a machine of the class described, 35 the combination of means for gripping the margin of a flat upper, a shoe forepart form having undercut portions and movable relatively to the gripping means to draw the upper from the gripping means and stretch 40 it in a direction perpendicular to the bottom of the shoe form, form embracing wipers for wiping the stretched upper on the form in a direction toward the bottom of the form and arranged for closing movement to shape the 45 upper to the undercut portions of the form, and means for forming the portion of upper extending beyond the bottom of the form outward against the bottom face of the wipers to form an outwardly directed flange 50 upon the upper.

16. In an upper forming machine, a form having the shape which the forepart of the upper is to assume in the finished shoe, clamping jaws arranged to embrace the form, and receive a flat upper overlying the form, 55 means for moving the form and jaws relatively to cause the upper to be wrapped about the form and progressively drawn from the jaws until its marginal portion assumes a 60 position substantially perpendicular to the bottom of the form, and means for ironing the perpendicularly disposed portion of the upper.

17. In an upper forming machine, a form 65 having the shape which the forepart of the

upper is to assume in the finished shoe, clamping jaws arranged to embrace the form and receive a flat upper overlying the form, means for moving the form and jaws relatively to cause the upper to be wrapped 70 about the form and progressively withdrawn from the jaws, and heated means for ironing the upper as it is withdrawn from the jaws.

18. In an upper forming machine, a form 75 having the shape which the forepart of the upper is to assume in the finished shoe, clamping jaws arranged to embrace the form and receive a flat upper overlying the form, means for moving the form and jaws 80 relatively to cause the upper to be wrapped about the form and progressively withdrawn from the jaws, heated means for ironing the upper during its withdrawal from the jaws, and means for forcing the upper yieldingly 85 against the heated ironing means.

19. In an upper forming machine, a form having the shape which the forepart of the upper is to assume in the finished shoe, upper gripping means arranged to receive the 90 marginal portions of the upper, means for moving the form and the gripping means relatively to cause the upper to be wrapped about the form and progressively withdrawn from the gripping means, means for 95 subjecting the upper during its withdrawal to the action of moist heat, means for ironing the upper as it leaves the gripping means and applying dry heat to the upper, means 100 for wiping the upper at the end and sides of the form toward the bottom of the form, means for bending outwardly the portion of the upper extending beyond the bottom of the form and pressing it against the 105 wiping means, and means for heating the wiping means.

20. In an upper forming machine, a form having the shape which the forepart of the upper is to assume in the finished shoe, upper gripping means arranged to receive the 110 marginal portions of the upper, means for moving the form and the gripping means relatively to cause the upper to be wrapped about the form and progressively withdrawn from the gripping means, means for ironing the upper as it leaves the gripping means, means for wiping the upper at the end and sides of the form toward the bottom of the form, means for bending outwardly the portion of the upper extending beyond the bottom of the form and pressing it against the wiping means, and means for heating the wiping means.

21. In an upper forming machine, a form having the shape which the forepart of the upper is to assume in the finished shoe, upper gripping means arranged to receive the marginal portions of the upper, means for moving the form and the gripping means relatively to cause the upper to be wrapped 115

about the form and progressively withdrawn from the gripping means, means for subjecting the upper during its withdrawal to the action of moist heat, means for wiping the upper at the end and sides of the form toward the bottom of the form, and means for bending outwardly the portion of the upper extending beyond the bottom of the form and pressing it against the wiping means.

22. In an upper forming machine, a form having the shape of the forepart of a shoe adapted to receive a flat upper in a position overlying the form, ironing means, means for tensioning the upper about the form and arranged to release the upper to the ironing means, means for applying intense drying heat to the ironing means, and wiping means heated to a temperature less than that of the ironing means acting in conjunction with the ironing means to shape the upper to the form and to hold the upper in form conforming position to be set by the heat of the wipers, and means for turning out the margin of the upper extending beyond the bottom of the form against the heated wipers.

23. In an upper forming machine, a form having the shape of the forepart of a shoe adapted to receive a flat upper in a position overlying the form, ironing means, means for tensioning the upper about the form and arranged to release the upper to the ironing means, means for applying relatively high drying temperature to the ironing means, and wiping means heated to a temperature less than that of the ironing means acting in conjunction with the ironing means to shape the upper to the form and to hold the upper in form conforming position to be set by the heat of the wiping means.

24. In a machine of the class described, the combination of an upper gripper, a toe embracing ironing means, a toe embracing wiping means arranged for closing movement, a form having the shape of the forepart of a shoe including the receding or undercut portions adjacent to the bottom of the form, means for relatively moving the form and the other mentioned elements to bring an upper overlying the form into position for successive operations of the elements in the order named, means for operating the gripping, ironing and wiping means to do their work, and means for effecting relative adjustment of the form and the gripping, ironing and wiping means longitudinally of the form.

25. In an upper forming machine, a form having the shape of the forepart of a shoe adapted to receive a flat upper in a position overlying the form, wiping means, means for tensioning the upper about the form and arranged to release the upper to the wiping means, means for applying dry heat to the

upper as it passes from the tensioning means to the wiping means, and means for turning out the margin of the upper extending beyond the bottom of the form against the wiping means.

70

26. In an upper forming machine, a form having the shape of the forepart of a shoe adapted to receive a flat upper in a position overlying the form, wiping means, means for tensioning the upper about the form and arranged to release the upper to the wiping means, means for applying heat to the wiping means to set the upper to the form, and means for turning out the margin of the upper extending beyond the bottom of the form against the heated wiping means.

75

27. In an upper forming machine, a form having the shape of the forepart of a shoe adapted to receive a flat upper in a position overlying the form, means for applying moist heat to the unformed upper to soften it, wiping means, means for tensioning the upper about the form and arranged to release the upper to the wiping means, and means for turning out the margin of the upper extending beyond the bottom of the form against the wiping means.

80

90

28. In an upper forming machine, a form having substantially the shape which the forepart of the upper is to assume in the finished shoe, yieldingly actuated upper holding means arranged to embrace the form and adapted to receive the marginal portion of an upper and hold it yieldingly, means for moving the form and holding means relatively to cause the upper to be wrapped about the form and to be progressively withdrawn from the holding means, and means automatically operative in such relative movement of the form and the holding means to wipe the upper toward the bottom of the form.

95

100

105

29. In an upper forming machine, a form having the shape which the forepart of the upper is to assume in the finished shoe, clamping means embracing the form adapted to receive the marginal portion of the upper, said clamping means comprising upper and lower plates one of which is ribbed, and means for moving the form and clamping means relatively to cause the upper to be wrapped about the form and progressively withdrawn from the clamping means.

110

115

30. In a machine of the class described, the combination of upper confining means, a former, means for relatively moving the confining means and the former to withdraw the upper from the confining means, and means acting during the relative movement of the former and the confining means to press the upper at the end and sides of the toe against the end and sides of the former.

120

125

31. That improvement in methods of making shoes which includes as a preliminary

130

- 5 step preparatory to lasting, confining the margin of a shoe upper, shaping the unconfin ed portion to the shape of the forepart of the shoe while allowing the upper to withdraw from confinement, and applying wiping pressure to the end and sides of the forepart.

10 32. That improvement in methods of making shoes which includes as a preliminary step preparatory to lasting, confining the margin of a shoe upper, shaping the unconfin ed portion to the shape of the forepart of the shoe by relative movement of a former and the confining means substantially perpendicular to the sole face of the former, and applying rubbing pressure to the end and sides of the former additionally to tension the upper during said relative movement.

15 33. That improvement in methods of preparing shoe uppers for lasting which includes confining the margin of a flat upper, and relatively moving the confined and the unconfined portions to form a toe pocket in the upper while ironing the outer face of the upper and permitting the confined portion to withdraw from confinement.

20 34. That improvement in methods of preparing shoe uppers for lasting which includes confining the margin of a flat upper, relatively moving the confined and unconfined portions to form a toe pocket in the upper while ironing the outer surface of the upper and permitting the confined portion to withdraw from confinement, and reducing the periphery of the toe pocket adjacent to the plane of the shoe bottom.

25 35. That improvement in methods of forming uppers preparatory to lasting which includes confining the margin of the upper, subjecting the exterior of the unconfined portion to the action of moist heat, and forming the unconfined portion in the shape of the end of the shoe while withdrawing the confined margin from confinement and forming it into an upstanding edge about the end of the shoe.

30 36. That improvement in methods of forming uppers preparatory to lasting which includes confining the margin of the upper, subjecting the exterior of the unconfined portion to the action of moist heat, forming the unconfined portion to the shape of a shoe toe while withdrawing the confined margin from confinement and forming it into an upstanding edge about the shoe toe, and applying drying heat to the side and end portions of the toe upper thus formed.

35 37. That improvement in methods of preparing shoe uppers for lasting which includes confining the margin of a flat upper, relatively moving the confined and unconfined portions to form a toe pocket in the upper, reducing the periphery of the toe

40 pocket adjacent to the plane of the shoe bottom, then turning outwardly the margin of the upper beyond the reduced periphery, and holding the outturned flange under pressure to set the flange in its shaped position.

45 38. That improvement in methods of preparing shoe uppers for lasting which includes confining the margin of an upper, relatively moving the confined and unconfined portions to form a toe pocket in the upper while applying rubbing pressure to the outer face of the upper and permitting the confined portion to withdraw from confinement, turning the margin of the upper at right angles to the sides of the pocket to form a flange, and subjecting the flange to the action of heat to set the flange in shaped position.

50 39. That improvement in methods of preparing shoe uppers for lasting which includes confining the margin of an upper, relatively moving the confined and unconfined portions to form a toe pocket in the upper while ironing the outer face of the upper and permitting the confined portion to withdraw from confinement, turning the margin of the upper at right angles to the sides of the toe pocket to form a flange, and subjecting the flange to the action of heat and pressure to set the flange.

55 40. That improvement in methods of molding the toe portion of upper materials off the last to give them substantially the shape which they are to have in the finished shoe which consists in wiping an upper over the end and side faces of a form to work the upper into conformity to the contour of the form and then holding the upper against the form to prevent it from relaxing, and while thus holding the upper molding its marginal portion into a sole attaching flange.

60 41. That improvement in methods of molding the toe portion of upper materials off the last to give them substantially the shape which they are to have in the finished shoe, which consists in gripping the margin of an upper about the toe end and drawing the upper over a form, wiping the upper over the end and side faces of the form, and then molding the marginal portion of the upper into a sole attaching flange.

65 42. That improvement in methods of molding the toe portion of upper materials off the last to give them substantially the shape which they are to have in the finished shoe which consists in gripping the margin of an upper about the toe end and drawing the upper over a form, wiping the upper over the end and side faces of the form and then holding it pressed against said faces, and while thus holding the upper shaping its marginal portion between rigid molding instrumentalities to produce a sole attaching flange.

43. That improvement in methods of molding the toe portion of upper materials off the last to give them substantially the shape which they are to have in the finished shoe
 5 which consists in clamping the margin of an upper about the toe end and drawing the upper over a form while giving up stock from the clamped margin, embracing the toe of the upper and wiping it heightwise of the
 10 form while drawing the upper over the form, and thereafter molding the marginal portion of the upper into a sole attaching flange.

44. In a machine for molding the toe portion of upper materials off the last to give them substantially the shape which they are to have in the finished shoe, the combination with a form, of means for clamping the marginal portion of an upper about the toe end, operating mechanism for effecting relative movement of said clamping means and the form in the direction of the height of the form to draw the upper over the form, means for wiping the upper over the end and side faces of the form, and means arranged for subsequent operation to mold the marginal portion of the upper into a sole attaching flange.

45. In a machine for molding the toe portion of upper materials off the last to give them substantially the shape which they are to have in the finished shoe, the combination with a form, of a device for clamping the marginal portion of the upper about the toe end, operating mechanism for effecting relative movement of said clamping device and the form to draw the upper over the form, means for wiping the upper heightwise of the form and for then holding it against the form, and additional means arranged to be operated while the upper is thus held to mold the marginal portion of the upper into a sole attaching flange.

46. In a machine for molding the toe portion of upper materials off the last to give them substantially the shape which they are to have in the finished shoe, the combination with a form, of means for clamping the marginal portion of the upper about the toe end, operating mechanism for effecting relative movement of said clamping means and the form to draw the upper over the form, a device automatically operative in such relative movement of the clamping means and the form to wipe the upper heightwise of the form, and means automatically operative thereafter to mold the marginal portion of the upper into a sole attaching flange.

47. In a machine for molding the toe portion of upper materials off the last to give them substantially the shape which they are to have in the finished shoe, the combination with a form, of means for gripping the marginal portion of the upper and drawing the upper over the form, means for wiping the upper heightwise of the form comprising

ing a wiping device constructed to present a wiping face of substantially unvarying contour close to the end and side faces of the form throughout the wiping operation, and means arranged for operation after the wiping of the upper heightwise of the form to mold its marginal portion into a sole attaching flange. 70

48. In a machine for molding the toe portion of upper materials off the last to give them substantially the shape which they are to have in the finished shoe, the combination with a form, of means for ironing the margin of the upper in a position perpendicular to the bottom of the form, and means for turning and clamping the margin of the upper extending beyond the bottom of the form in a position parallel to the bottom of the form. 75

49. In a machine for molding the toe portion of upper materials off the last to give them substantially the shape which they are to have in the finished shoe, the combination with a form, of a member having a surface embracing the form and across which the upper is drawn by relative movement of the member and form, and means acting against the inner side of the upper to force it against said surface and maintain it under tension. 85

50. In a machine for molding the toe portion of upper materials off the last to give them substantially the shape which they are to have in the finished shoe, the combination with a form, of a member having a surface embracing the form and across which the upper is drawn by relative movement of the member and form, means acting against the inner side of the upper to force it against said surface to maintain it under tension, and wipers arranged to co-operate subsequently with said means to clamp the upper margin in outturned relation to the form. 95 100 105

51. In a machine for molding the toe portion of upper materials off the last to give them substantially the shape which they are to have in the finished shoe, the combination with a form, of a plurality of upwiping devices operating successively to work the upper heightwise of the form. 110

52. In a machine for molding the toe portion of upper materials off the last to give them substantially the shape which they are to have in the finished shoe, the combination with an undercut form, of two upwiping devices operating successively upon the upper, one constructed and arranged to tension the upper and dispose its margin perpendicular to the bottom of the form and the other comprising wipers operated to close yieldingly against the form and acting 115 120 125 to wipe the upper heightwise of the form including undercut portions of the form.

53. In a machine for molding the toe portion of upper materials off the last to give them substantially the shape which they are 130

to have in the finished shoe, the combination with a form, of means for clamping the upper substantially in a plane parallel with the bottom of the form, means for relatively 5 moving the form and clamping means to shape the upper over the form and cause it to withdraw from the clamping means, and means for holding the margin of the upper as it withdraws from the clamping means in 10 a position substantially perpendicular to the bottom of the form.

54. In a machine for molding the toe portion of upper materials off the last to give them substantially the shape which they are 15 to have in the finished shoe, the combination with upper margin confining means and a form relatively movable to cause the upper to be wrapped about the form, of a plurality of wiping devices operating successively 20 to work the upper heightwise of the form toward the bottom of the form.

55. In a machine for molding the toe portion of upper materials off the last to give them substantially the shape which they are 25 to have in the finished shoe, the combination with a form, of two wiping devices operating successively upon the upper during relative movement of the form and said devices, one device constructed and arranged 30 to tension the upper and dispose its margin perpendicular to the bottom of the form and the other device comprising wipers arranged to close against the form and acting to wipe the upper heightwise of the form.

56. In a machine for molding the toe portion of upper materials off the last to give them substantially the shape which they are to have in the finished shoe, the combination with a form, of means for clamping the upper 40 substantially in a plane parallel with the bottom of the form, means for moving the form relatively to the clamping means, an ironing device of fixed contour embracing the upper, and means for holding the margin of the upper as it withdraws from the clamping means against the ironing device in a position substantially perpendicular to the bottom of the form.

57. In a machine for molding the toe portion of upper materials off the last to give them substantially the shape which they are to have in the finished shoe, the combination with a form, of means for clamping the upper, means for moving the form relatively to 55 the clamping means to stretch the upper over the form, an ironing device of fixed contour embracing the upper, means for holding the margin of the upper as it withdraws from the clamping means against the ironing device in a position substantially perpendicular to the bottom of the form, and wiping means having a closing movement against the form as the form continues to move, to shape the upper to the form and 60 work the upper heightwise of the form.

58. In a machine for molding the toe portion of upper materials off the last to give them substantially the shape which they are to have in the finished shoe, the combination with a form, of two upwiping devices operating successively upon the upper, one comprising a fixed outer member and an expanding inner member to tension the upper and dispose its margin perpendicular to the bottom of the form and the other comprising 75 wipers having a closing movement against the form and operating to wipe the upper heightwise of the form.

59. In a machine for molding the toe portion of upper materials off the last to give them substantially the shape which they are to have in the finished shoe, the combination with a form, of means for clamping the upper substantially in a plane parallel with the bottom of the form, means for relatively 80 moving the form and clamping means, a fixed outer member and an expanding inner member co-operating to hold the margin of the upper as it withdraws from the clamping means in a position substantially perpendicular to the bottom of the form, and a pair of wipers co-operating with said inner member to mold the margin of upper extending beyond the bottom of the form into a sole attaching flange.

60. In a machine for molding the toe portion of upper materials off the last to give them substantially the shape which they are to have in the finished shoe, the combination with a form, of an ironing member having 90 a surface embracing the form and across which the upper is drawn by relative movement of the member and form, an expanding member acting against the inner side of the upper to force the upper against the surface 100 of the ironing member and maintain it under tension, means for operating said expanding member after said relative movement has carried the margin of the upper beyond the ironing member to turn outwardly the margin of the upper, and means co-operating with the expanding member to clamp the margin of the upper in outturned relation to the form.

61. In a machine for molding the toe portion of upper materials off the last to give them substantially the shape which they are to have in the finished shoe, the combination with a movable form, of a member having a surface embracing the form and across 110 which the upper is drawn by movement of the form, expanding means for holding the upper against the surface and maintaining it under tension, and wipers cooperating with said upper expanding means upon further movement of the form and after further expansion of said means to clamp the upper margin in outturned relation to the form.

62. In a machine for molding the toe por-

tion of upper materials off the last to give them substantially the shape which they are to have in the finished shoe, the combination with a movable form, of an ironing member having a surface of fixed contour embracing the form and across which the upper is drawn by movement of the form, pressing means acting yieldingly against the inner side of the upper to hold it against said ironing surface and maintain it under tension, wiping means operated yieldingly against the form as movement of the form

continuous to work the upper heightwise of the form, and means for effecting further movement of said pressing means positively 15 after movement of the form ceases to cause said pressing means to co-operate with the wiping means to clamp the upper margin in outspread position substantially in the plane of the bottom of the form. 20

In testimony whereof I have signed my name to this specification.

MATTHIAS BROCK.
